Patented Feb. 1, 1927.

UNITED STATES PATENT OFFICE.

HENRY WILCOX METCALF, OF HONOLULU, TERRITORY OF HAWAII.

WINDOW SHADE.

Application filed November 6, 1925. Serial No. 67,407.

This invention relates to window shades and has for its broad object the provision of an article of the class designated which, while admitting air and diffused light with practically no impediment, at the same time totally excludes the glare from direct sun light, and entirely occludes the visibility of objects through the shade.

A more specific object of the invention is the provision of a window shade constructed with vertically telescopic sections having means for limiting the range of opening movement of the sections so that one always intersects the plane of the lower edges of another, whereby a continuous barrier is interposed to the passage through said shade of rays of light travelling in straight lines, while at the same time ample passages are provided between the several sections for the circulation of air and the reflection of diffused light.

A further object of the invention is the provision of telescopic sections tiltably mounted so that the weather sides thereof may be brought into close overlapping relation for the exclusion of draughts or wind-driven rainfall.

The invention also includes among its objects the provision of means for adjustably lowering the shade from the top, raising it from the bottom, or latching it in storm-closed position.

Other objects of the invention will appear as the following description of a preferred embodiment thereof proceeds.

In the drawings:—

Figure 1 is a front elevation of a casement equipped with a window shade embracing the principles of the present invention.

Figure 2 is a sectional elevation, part being broken away, showing the shade in closed position, with the operating means therefor.

Figure 3 is a section taken along the line 3—3 of Figure 2.

Figure 4 is a view similar to Figure 3, but showing the window shade raised from the bottom.

Figure 5 is a plan view of a portion of one of the telescopic sections.

Figure 6 is an enlarged sectional view of the lower portion of the window shade, slightly raised.

Figure 7 is a sectional view showing a detail of the lower portion of the window shade

with the parts tilted to a position in which the shade is latched in storm-closed position.

Figure 8 is an end view of the top section showing the cord attaching means and guide rollers.

Figure 9 is a plan view of the end portion shown in Figure 8.

Referring now in detail to the several figures, the numeral 1 represents a casement to which the device of the present invention is applied. The casement is furnished with an inwardly directed flange 2, 3 and 4, Figure 3, extending therearound except for a short distance at each side adjacent the bottom of the casement where there is a break 5. The purpose of this break in the continuity of said flange will be explained in due course. Said flange interleaves with the adjacent shade parts to totally exclude the passage of light or rain between the shade and the walls of the casement. The upper flange 2 is preferably positioned between channelled members 28 and 29, the latter being suitably secured to the wall of the casement and serving the purpose of housing for certain pulleys and portions of certain cords herein-after to be described, by means of which the shade is operated, thereby avoiding the necessity of mortising the casement, although if desired, the channelled members may be omitted, if mortising is to be practiced, in which case the flange 2 may be secured directly to the casement.

The window shade proper includes a top section 6, a bottom section 7 and intermediate telescopic sections 8, the latter sections each having the shape of an inverted trough or V section, the bottom section being telescopic within the section which lies immediately above it. The top section is preferably formed of sheet metal, as a parallelepipedal body extending the full width of the casement and having a slot 9 running longitudinally along the top side thereof, into which slot the flange 2 at the top of the casement extends when the top section 6 is in its uppermost position illustrated in Figure 3, thus forming a light and wind-tight joint between the top section and the lintel of the casement. The ends of the top section are provided with slots embracing the lateral flange portions 3 of the casement.

The uppermost of the telescopic sections 8 is loosely fastened along the apex of its

dihedral angle medially of the underneath surface of the top section by a series of fastening means such as bolts 11. In order to block the light which passes through the crack between the apex of the uppermost telescopic section and the top section, the latter is provided with a depending flange 12 intersecting the path of direct rays entering through said crack.

10 When the shade is folded the telescopic sections 8 nest one within the other, as shown in the lower part of Figure 4, and, when the shade is extended, they separate from one another by a distance permitted by the series of bolts 13, said bolts being loosely mounted in slots 14 (Figure 5) so that they hang substantially vertically in all positions of the telescopic sections and slip freely through the slots 14 when the sections are moved relatively to one another. The slots 14 on the inner or house side of the shade are cut directly through said sections adjacent the edges of the sections on the inner or house side of the latter, whereas 25 on the outer or weather side of the shade the slots 14 are formed in lugs 15 projecting from the edges of the sections on the outer or weather side of the shade. This is to facilitate the tilting of the sections to storm-closed position, as will presently be explained.

As shown in Figure 5, there are two slots 14 adjacent each end of each edge of each of the telescopic sections except the uppermost and lowermost of same, each slot being occupied by a bolt, as best shown in Figures 1 and 2. One of said bolts, designated as 16 in Figure 2, depends from the section 8 next above, whereas the other bolt, designated as 17 in said figure, suspends the section next below. As shown in Figures 1 and 2, the bolts of the several sections are progressively misaligned in order that they may, when the telescopic sections are nested, assume side-by-side positions without colliding. The edges of the sides of the telescopic sections are cut away at 19 to accommodate the bolts when they are in side-by-side position.

50 Each of the telescopic sections, viz: each of the sections except the uppermost section 6, has a groove 18 in each of its ends to receive one of the flange portions 3 and affording means whereby the shade is guided in a rectangular path by said flange portions.

There are two independent cords 20 and 25 each forming an endless belt, one arranged on each side of the lateral and top portions of the guiding flange. Each cord passes over a pair of single pulleys 21 mortised at opposite sides into the sill of the casement, and a pair of double pulleys 22, preferably housed in the channelled members 28 and 29. One limb of one cord, that is to say the cord designated by the reference

character 20 in Figure 5, passes through an apertured lug 30 formed on a block 31 carried at the end of the bottom section 7, said limb being fastened to said lug by a set screw 32. At the other side of the casement, the opposite limb of the same cord, which is travelling in the same direction, is similarly secured to the other end of the bottom section. Both ends of the bottom section being simultaneously raised or lowered by the operation of the cord 20. The top section 6 is provided at its ends with blocks 33 having projecting lugs 34 which are attached to those limbs of the other cord 25 which are travelling in the same direction. The blocks of both top and bottom sections are preferably furnished with rollers 35 which bear against the side flanges 3 in the ascent and descent of the shade, constituting non friction guide elements for said shade.

It is apparent from the above description that the shade may be lowered from the top by manipulating the cord 25 or raised from the bottom by manipulating suitable portions of the cord 20, the shade being raised or lowered, as the case may be, an even distance on both sides.

In the positions of the telescopic sections shown in Figures 3 and 4 and particularly in Figure 6, an open passageway is formed between the sides of adjacent sections permitting the free circulation of air from one side of the shade to the other and also permitting the entrance of diffused light reflected from the sloping sides of the telescopic sections. It is apparent that no direct rays of light can enter a room protected by the shade when it is in this position, nor can objects on one side thereof be observed from the other side, since light also travels in straight lines, and an apex of an underlying telescopic section intersects the plane embracing the lower edges of the sections immediately above it.

It is sometimes desirable, however, to exclude some of the air that otherwise would enter, as well as to shut out draft or a wind-driven rain. To accomplish this the telescopic sections, including the bottom section, are made tiltable so that the outer sides thereof assume an overlapping relation of shingle-like closeness. The cut away portions 19 are made sufficiently wide to permit this tilting movement of the sections. In order to latch the shade in storm-closed position the bottom section is lifted by hand until the slot 27 in said section which normally engages the bottom flange 5 is clear of said flange, whereupon the bottom section is tilted in the manner shown in Figure 7, passing through the break 5 in the lower ends of the flange portions 3 until it assumes the position shown in Figure 7, which position is retained by virtue of the

- engagement of the lower edge thereof with the flange portion 4. The tautness of the cord 20 caused by its deflection from the vertical when the bottom section is tilted, also assists in keeping said section in tilted position. To restore the bottom section to the normal position shown in Figure 6, it is necessary merely to pull down the inner end thereof by hand, simultaneously pushing it through the break 5 until the slot 27 is in alignment with the flange portions 3 whereupon the bottom section may be raised upwardly upon said flange portions or pushed downwardly upon the flange portion 4, according to the position of the shade desired. When the bottom section of the shade is in engagement with the flange portion 4 an absolutely weather-tight joint is formed between the shade and sill of the 20 casement.
- While I have herein described what I believe to be an efficient and practical embodiment of my invention, it is to be understood that the application of the inventive principle is not restricted to the construction herein disclosed, but that it may find physical expression in many forms to which the appended claims, or any one of them may be generic.
- Having described my invention what I claim as new and desire to secure by Letters Patent is:
1. In combination, a flange adapted to extend longitudinally of the sill of a casement, projecting toward the casement opening, and a vertically movable shade including a bottom section having a longitudinal slot to receive said flange in the lowermost position of said shade, other sections operably connected to said bottom section to perform similar movements to and synchronously with the movements of the bottom section, said bottom section being tiltable about a point in its line of vertical travel when out of engagement with said flange but near its lowermost position, and having a part thereof engaging said flange when said bottom section is tilted for holding said shade sections in tilted position.
  2. A window shade including a top section having a slot extending longitudinally of the upper face thereof to receive a flange at the top of a casement, a series of sections freely suspended from said top section, the uppermost of said depending sections being loosely connected to the bottom face of said top section along a line extending longitudinally thereof, said top section being provided with a flange extending downwardly at one side of the line of juncture between said suspended sections and said top section, and loosely connecting and intersecting a horizontal plane passing through said line of juncture.
  3. A window shade including a top sec-
- tion having a flat lower face, a series of pending sections, means carried by said top section for loosely connecting the uppermost of said depending sections to the lower face of said top section along a line extending longitudinally thereof, said top section being provided with a downwardly extending flange intersecting a horizontal plane passing through the line of juncture of said uppermost depending section with said top section.
4. A window shade including telescopic sections serially suspended, spaced lugs at the ends of said sections loosely embracing guide members for guiding said sections in a vertical path of movement, said sections being tiltable relative to said guide members and means for simultaneously tilting said sections.
5. A window shade including telescopic serially depending sections each having the shape of an inverted trough, said sections nesting together when telescoped and having slots adjacent their lower edges, rods loosely passing through said slots for limiting the range of extension of said sections, the edges of said sections being cut away to permit said rods to lie side by side when the sections are in fully telescoped position.
6. A window shade including a top section and a bottom section, intermediate telescopic serially depending sections loosely connected to said top and bottom sections, said intermediate sections each having the shape of an inverted trough, and having at their ends grooves for loosely embracing guide members for guiding said sections in a vertical path of movement, said intermediate and bottom sections having slots adjacent their opposite edges and being tiltable relative to said guide members, rods loosely engaging in said slots of said intermediate sections and said bottom section, said rods being of such length as to limit the extension of said telescopic sections so that the apex of one always intersects the plane passing through the lower edges of the section immediately above it, said rods functioning as means for simultaneously tilting the intermediate sections when the bottom section is tilted.
7. A window shade including a top section and a bottom section, intermediate telescopic serially depending sections loosely connected to said top and bottom sections, said intermediate sections each having the shape of an inverted trough, said intermediate sections having grooves in their ends for loosely embracing guide members for guiding said sections in a vertical path of movement, said intermediate and bottom sections being tiltable relatively to said guide members, lugs on the outer sides of said intermediate and bottom sections, said lugs and the opposite sides of said sections

being slotted, rods loosely engaging in said slots, said rods being of such length as to limit the extension of said telescopic sections so that the apex of one always intersects the plane passing through the lower edges of the section immediately above it, said rods functioning as means for simul-

taneously tilting the intermediate sections when the bottom section is tilted and said grooves permitting said sections to assume 10 a relatively closed position when tilted.

In testimony whereof I have hereunto set my hand.

HENRY WILCOX METCALF.
